UNITED STATES PATENT OFFICE.

CHARLES T. HARD, OF EAST LIVERPOOL, ASSIGNOR TO THOMAS H. HARD,
OF NEWBURG, OHIO.

COMBINED SOFA AND BED.

SPECIFICATION forming part of Letters Patent No. 400,079, dated March 26, 1889.

Application filed March 10, 1888. Serial No. 266,822. (No model.)

To all whom it may concern:

Be it known that I, CHARLES T. HARD, of East Liverpool, in the county of Columbiana and State of Ohio, have invented a new and 5 Improved Combined Sofa and Bed, of which the following is a full, clear, and exact description.

My invention relates to an improvement in combined sofas and beds, or what is known 10 in the trade as "sofa-beds."

The object of the invention is to provide an article of furniture which may be conveniently and expeditiously converted from a sofa to a bed, and vice versa, and wherein, 15 when used as a bed, the bottom will be amply supported and elevated essentially the same distance from the floor as the equivalent portion of an ordinary bed.

The invention consists in the construction 20 and combination of the several parts, as will be hereinafter fully set forth, and pointed out in the claims.

Reference is to be had to the accompanying drawings, forming a part of this specification, 25 in which similar letters of reference indicate corresponding parts in all the figures.

Figure 1 is a perspective view of the article when used as a sofa. Fig. 2 is a perspective view of the sofa converted into a bed. Fig. 30 3 is a section on line $x-x$ of Fig. 1. Fig. 4 is a section on line $y-y$ of Fig. 1. Fig. 5 is a section on line $z-z$ of Fig. 2. Fig. 6 is a detail view of one facing-board, and Fig. 7 is a detail perspective view of one of the braces 35 and its hinge.

In the invention the body B of the sofa-bed consists of a rectangular frame of suitable size provided with a head end piece, b , a foot end piece, b' , and one side piece, b^2 , connecting said ends.

Upon the foot b' of the body a board, E, is secured of essentially the same size as the foot-piece, and to one end of said foot-board E a second and similar board, a^3 , is hinged, 45 the one board being adapted to fold over upon the outer face of the other, or outward in the same plane, as occasion may demand. A head-board, d' , preferably of greater height than the head-piece b and of equal length, is 50 attached to said head-piece, and a second and

similar head-board, d , is hinged to the aforesaid head-board d' , the board d being purposed to fold over upon the board d' in like manner as the two foot-boards E and a^3 . Upon the upper or smooth face of the body 55 B, at the head, a hollow block, B' , is secured in any approved manner, which block is shaped to the contour of a comfortable head-rest, as illustrated in Figs. 1 and 3. The outer end of the head-rest B' is preferably carried 60 beyond the end of the body and provided with an opening, w , whereby the said head-rest may be adapted for use also as a receptacle for light articles employed in dressing 65 the bed.

A second rectangular frame, which for convenience I denominate a "base-frame," A, is constructed in similar manner to the body-frame B, consisting of a bottom, two end pieces, a and a' , and one side piece, a^2 . The 70 body and base frames are united by a hinge, e , preferably a rule-hinge, secured, respectively, to the head and foot pieces of the frames proper at the unfinished side, as best illustrated in Fig. 2.

At each side of the body a facing-board, D, is hinged, so as to swing vertically upward or downward, as occasion may require. When converted into a sofa, the facing-boards can be turned down, as shown in full lines in Fig. 1, 80 so as to conceal the base; or, instead of turning both of the facing-boards down, the rear one may be turned upward into a vertical position to form a back for the sofa, as shown in dotted lines in said figure. The boards D 85 serve as supports for the body when converted into a bed.

In one side of the facing-boards a longitudinal recess, o' , is formed. To the facing-boards adjacent the said recesses brace-strips o are 90 hinged, which brace-strips are provided with caster-wheels o^2 , and are adapted when not in use to lie within the said recess o' parallel with the facing-boards, as clearly shown in Fig. 6.

The strips o are secured to one strap or leaf of the strap-hinge O^4 , and the other leaf or strap is pivoted at O^5 to the facing-boards D. When the strips O are in use, as illustrated in Figs. 2 and 5, they are first turned 100

outward on their pivots O^5 at right angles to the facing-boards and then swung inward and under the said facing-boards on the hinge-pintle, so that the strips on the two boards 5 will project toward each other and their ends abut against each other, as clearly shown in the drawings.

The brace-strips are removed from their recess only when the sofa is converted into a 10 bed, whereupon the strips of the opposing facing-boards abut, and may, if desired, be secured by braces O^3 .

When it is desired to convert the sofa shown in Fig. 1 to the bed illustrated in Fig. 2, the 15 body-section B is thrown from off the base-section A, the front board, D, having first been raised to the position illustrated to the right of Fig. 1 in dotted lines, whereupon the body is supported by the two facing-boards, as 20 shown in Fig. 2, and the base-section A by the now central facing-board, D, and suitable folding legs, which may be pivoted within the side pieces, a^2 . When the base and body are 25 in this position, their horizontal bottom surfaces are in the same plane and the unfinished sides are brought in engagement with the upper faces of the centrally-located facing-board, D. Within the compartment thus formed the springs and mattress are placed 30 in any approved manner, and a roomy bed is thereby provided, supported centrally and at the sides. To complete the bed, the foot-board a^3 is carried outward from the similar board, E, attached to the foot-piece b' , and the said 35 foot-board a^3 is secured in any suitable manner parallel with the end piece, a' , as illustrated in Fig. 2. The head-board d is folded outward in like manner and secured to the head-piece a . In reconverting the article 40 into a sofa, the foot-board a^3 is folded upon the board E, and the head-board d likewise folded back upon the board d' , and the legs are folded up within the base. The body is now thrown over upon the base, whereupon 45 the head-boards are concealed by the head-rest, as best shown in Fig. 3.

The facing-board at the front of the sofa is folded down, as shown in Fig. 1, and, if desirable, the rear facing-board is carried upward 50 in connection with the head-rest, as illustrated in dotted lines in Fig. 1, to form a back for the sofa.

I do not confine myself to any form of legs for supporting the base when the device is converted into a bed, and the entire structure 55 may be braced and strengthened in any approved manner.

Having thus described my invention, what I claim as new, and desire to secure by Letters Patent, is—

1. In a combined sofa and bed, the combination of a body, a base-section hinged to one side or edge of the body, facing-boards hinged to opposite sides of the body and serving to conceal the base when used as a sofa and 65 supports for the body when used as a bed, and sectional and hinged head and foot boards on body and base sections, respectively, substantially as described.

2. In a combined sofa and bed, the combination, with the body and base section, each having one open side or edge and hinged together at their open sides or edges, of facing-boards hinged to opposite sides of the body and serving to conceal the base when used as 75 a sofa and supports for the body when used as a bed, pivoted and hinged braces for holding and supporting the facing-boards, and sectional and hinged head and foot boards on the body and base section, respectively, 80 substantially as herein shown and described.

3. In a combined sofa and bed, the combination, with a base-section and a body hinged together, of facing-boards hinged to the said body and brace-strips hinged to the said facing-boards, the strips of the opposing facing-boards abutting when the said strips are extended, substantially as herein shown and described.

4. In a combined sofa and bed, the combination, with a base-section, A, having an open side and provided with pivoted legs, of the body B, hinged to the base-section and having an open side, the head and foot boards b d' and b' E , the facing-boards hinged to the 95 body and provided with the hinged brace-strips o , and the boards a^3 d , hinged to the foot-board E and head-board d' , respectively, substantially as herein shown and described.
